(57) **CLAIM**

The ornamental design for a trigger-actuated dispensing nozzle, as shown and described.

DESCRIPTION

FIG. 1 is a front elevation view of a trigger-actuated dispensing nozzle of the present invention;

FIG. 2 is a first side elevation view of the trigger-actuated dispensing nozzle;

FIG. 3 is a rear end elevation view of the trigger-actuated dispensing nozzle;

FIG. 4 is a second side elevation view of the trigger-actuated dispensing nozzle;

FIG. 5 is a top plan view of the trigger-actuated dispensing nozzle; and,

FIG. 6 is a bottom plan view of the trigger-actuated dispensing nozzle.

The evenly broken lines are shown for the purpose of illustrations of parts of the article that form no part of the claim. The dot-dash broken lines are shown for the purpose of illustrating environmental structure and form no part of the claim.
